Edward C. Sarnett
Attorney

UNITED STATES PATENT OFFICE.

EDWARD R. VIVES, OF NEW YORK, N. Y., ASSIGNOR TO VESDAL CREATIONS, INC., OF NEW YORK, N. Y., A CORPORATION OF NEW YORK.

KEY.

Application filed September 6, 1923. Serial No. 661,219.

To all whom it may concern:

Be it known that EDWARD R. VIVES, a subject of the King of Spain, and a resident of New York, in the county of New York and State of New York, has invented a certain new and useful Key, of which the following is a specification.

The present invention relates to keys for combination locks of the multiple-key type.

In my copending application, Serial No. 658,654, filed Aug. 21, 1923, I have described and claimed a combination lock in which the combination may be changed by certain simple manipulations, each combination requiring a key individual thereto. The lock described comprises a barrel adapted when rotated to operate a bolt. The barrel is formed with an axial key way and with a longitudinal slot communicating with the key way and opening at the periphery of the barrel, said slot being filled with tumblers which are adapted to be moved radially of the barrel when a key is inserted by the engagement therewith of projections or teeth on the upper edge of the key. To operate the combination it is necessary to move certain tumblers and to leave unaffected the remainder, the particular tumblers to be operated depending upon the combination. The key for a given combination, therefore, must have its projections or teeth so arranged that when the key is inserted the necessary tumblers will be operated and the remainder of the tumblers will be unaffected.

The present invention relates to a key or key form adapted to be used with a lock such as described in my copending application. The object of the present invention, in general, is to provide a key form of simple and cheap construction which is adapted to be converted with facility into a key corresponding to any given combination for which the lock is set. More particular objects and advantages of the invention will become apparent hereinafter.

Referring to the accompanying drawings for a specific disclosure of some key forms which I have chosen to embody my invention,

Figure 1 is a longitudinal section of a lock barrel, showing in elevation a key inserted therein.

Figure 2 is a side elevation of a key form showing certain modifications. 55

Figure 3 is a side elevation of another key form.

In the drawings the key is shown on an enlarged scale.

Figure 1 illustrates in longitudinal section the barrel 10 of a lock constructed in accordance with the copending application referred to above. This barrel is formed with an axial key way and with a wider longitudinal slot communicating with said key way and opening through the barrel. Said slot is filled with tumblers 11, which are adapted to coact with tumblers 12. The particular tumblers 12 which are brought into registration with tumblers 11 will depend upon the combination desired, as is fully set forth in my copending application above cited. As will be understood from my copending application, each ward is provided with two angularly spaced inwardly 75 opening slots, in only one of which there is a tumbler 12. In one position of the wards the tumblers 12 are opposite the tumblers 11 and normally project into the slot of barrel 10; preventing rotation thereof. In 80 the other position of the wards the slots therein which do not carry tumblers are opposite the corresponding tumblers 11, so that if any one of these tumblers is moved it will project into the slot of its ward and thereby lock the barrel against rotation. The combination of the lock therefore is determined by the positions of the wards. 85

A key for any given combination should have teeth adapted to raise those tumblers 90 11 which have tumblers 12 in registration therewith, and should have spaces adapted to leave unaffected those tumblers 11 which have no registering tumblers 12. Accordingly, the key shown in Figure 1 has teeth 95 14 adapted to raise those tumblers 11 which are opposite tumblers 12, and has spaces adapted to leave unaffected the remaining tumblers 11. Figures 2 and 3 show a key form provided with a full set of teeth on 100 its upper edge, the number of teeth being the same as the number of tumblers 11. Such a key form may be converted into a key corresponding to any given combination simply by breaking off the necessary teeth. To 105 facilitate the breaking off of the teeth, the

latter may be joined to the blade of the key by reduced portions, formed, for example, by scoring the teeth along the bases thereof, as indicated by the dotted line 15. The user of the lock would be furnished with a number of these key forms, or they could be obtained from the dealer as required. Of course it would not be necessary to use a new key form, such as shown in Figures 2 and 3, every time the combination is changed, it being obvious that one key form could be used for a number of different combinations.

Figure 3 shows a key form adapted to be used with a lock barrel having a key way with plane bottom, the lower edge of the key in this view being straight. In order to make the combination more difficult to solve, I may form the key with irregularities or undulations 16 on its lower edge, as shown in Fig. 1, and form the barrel 10 with complementary irregularities or undulations in the bottom of the key way. Obviously in a lock of this construction the combination cannot be solved except by a key which not only has its teeth and spaces corresponding to the positions of the wards, but also has an irregular or undulating lower edge which exactly fits the irregularities in the bottom of the key way so as not to lift tumblers 11 too far. In Fig. 2 the key is provided with projections 16' of somewhat different form from those of Fig. 1. In so far as the present invention is concerned the key may have any number or form of projections. In practice the locks will be manufactured with several different numbers or forms of recesses or undulations in the bottom of the key ways and of course the keys will be made with corresponding irregularities or undulations. In a lock system of this character it would be necessary to identify the keys with the corresponding locks. This may be done by stamping or

otherwise affixing to the locks of one style and the keys corresponding thereto a common identification mark or number.

Now having particularly described my invention, what I claim as new and desire to secure by Letters Patent is:—

1. A key blank consisting of a shank or blade provided along the upper edge thereof with a plurality of detachable teeth of uniform length, the ends of said teeth defining a line substantially parallel with said edge.

2. A key form consisting of a handle and a blade and a plurality of regularly spaced easily detachable teeth of uniform length projecting from the edge of said blade, said parts forming an integral structure.

3. A key form consisting of a handle and a shank or blade and a plurality of regularly spaced teeth of uniform length along the upper edge of said blade and joined thereto by reduced portions.

4. A key having a shank or blade provided with a plurality of teeth along the upper edge thereof and having a plurality of projections along its lower edge.

5. A key having a shank or blade provided with a plurality of teeth along the upper edge thereof and having undulations in its lower edge.

6. A key form consisting of a handle and a blade, said blade having a plurality of regularly spaced easily detachable teeth on its upper edge and having a plurality of projections along its lower edge.

7. A key form consisting of a handle and a blade, said blade having a plurality of regularly spaced easily detachable teeth on its upper edge and having an undulating lower edge.

In testimony whereof I hereunto affix my signature.

EDWARD R. VIVES.
